United States Patent Office.

LEVI GRISWOLD, OF PORTLAND, AND G. CAUL, OF YORK, WISCONSIN.

Letters Patent No. 67,043, dated July 23, 1867.

IMPROVEMENT IN CUT-OFF VALVES.

The Schedule referred to in these Letters Patent and making part of the same.

TO ALL WHOM IT MAY CONCERN:

Be it known that we, L. GRISWOLD, of Portland, in the county of Dodge, and State of Wisconsin, and G. CAUL, of York, in the county of Dane, and State of Wisconsin, have invented a new and improved Steam Cut-Off; and we do hereby declare that the following is a full, clear, and exact description thereof, which will enable others skilled in the art to make and use the same, reference being had to the accompanying drawings, forming part of this specification.

This invention relates to the manner in which the steam is admitted to the working cylinder, and to the manner in which it is controlled and exhausted; and it consists in providing a steam-chest with cylinders and pistons (or valves) and apertures, and arranging them in such a manner that the valves or pistons which admit and cut off the steam shall not be subject to undue friction, in consequence of the pressure of the steam; and also so that the steam is made to operate upon the main shaft when the crank is in the centre, as will be hereinafter more fully described.

Figure 1 represents a vertical longitudinal section of our arrangement through the line xx of fig. 2, showing the course of the steam by arrows.

Figure 2 is a section of fig. 1 through the line yy .

Figure 3 is a detailed view of the lower cylinder, showing a top view of it in section through the line $z'z'$ of fig. 1.

Figure 4 shows the upper cylinder detached, it being also a top view in section through the line zz of fig. 1. Similar letters of reference indicate like parts.

A represents the steam or induction pipe. B is the steam-chest proper. C is a cylinder in B, with rod and pistons or valves. This rod is marked D, and it is operated or moved by hand. E represents another cylinder, under C, which also has a rod and piston-valves on it, and which is also moved by hand when it is desired to change its position. F represents another cylinder, under E, also with rod and piston-valves attached. Another view of this cylinder is shown in fig. 3. Between this cylinder F and the upper cylinder C there is an outside pipe communication, marked f, seen in dotted lines in fig. 1, standing at an angle on the steam-chest, which shows the course of the exhaust steam. The piston-valves in the lower cylinder F are operated by the rod, through a connection with the crank from the engine. These valves, covering the steam-ports, are plainly shown in fig. 3. The steam from the cylinder is exhausted in this cylinder F between the piston-valves, from whence it is conducted through the pipe f into the upper cylinder C, from whence it passes in the exhaust pipe marked G, and is discharged. aa represent the steam-ports leading to the engine cylinder. When the crank of the engine is standing on a dead-centre the piston-valve rod in E is drawn out or pushed in by hand, in order to throw the force of the steam upon either of the valves in F. The rod D in the upper cylinder, through the piston-valves on it, is moved by hand when it is desired to open or close either of the ports or apertures through that cylinder. It will be noticed that the lower or cut-off valves in the cylinder F, which are operated by the engine, are balanced by the pressure of steam, and work with very little friction.

Having thus described our invention, what we claim as new, and desire to secure by Letters Patent, is—

1. The cylinders C, E, and F, with the piston-valves and rods, constructed and arranged substantially as described, for the purposes set forth.

2. In combination with the above, we claim the pipe f, as herein set forth, for the purpose specified.

LEVI GRISWOLD,
G. CAUL.
